UNITED STATES PATENT OFFICE.

THOMAS E. BREEN, OF PHILADELPHIA, PENNSYLVANIA, AND GEORGE A. MARTIN, OF PEARL RIVER, NEW YORK, ASSIGNORS TO DEXTER FOLDER COMPANY, OF PEARL RIVER, NEW YORK, A CORPORATION OF NEW YORK.

SLOW-DOWN AND SHEET-STRAIGHTENER FOR FEEDING-MACHINES.

1,231,559.

Specification of Letters Patent.

Patented July 3, 1917.

Application filed January 10, 1916. Serial No. 71,250.

To all whom it may concern:

Be it known that we, THOMAS E. BREEN and GEORGE A. MARTIN, residing at Philadelphia, in the county of Philadelphia, 5 State of Pennsylvania, and at Pearl River, in the county of Rockland, State of New York, respectively, have invented certain new and useful Improvements in Slow-Down and Sheet-Straighteners for Feeding-10 Machines, of which the following is a full and clear specification.

This invention relates to slow down and sheet straightener machines in which laterally spaced carriages are suitably mounted 15 to reciprocate longitudinally of the paper feed and carry sheet-engaging members which are movable into and out of engagement with the paper during these reciprocating movements. The primary object of 20 this invention is to provide an improved construction, combination and arrangement of parts in a device of this character in which the slow down of a sheet is accomplished by means of gages which move into 25 and out of positions to intercept the forward edge of said sheet, the operation of this mechanism being adapted to present the sheet with its forward edge substantially parallel to the front gage 62 of a printing 30 press or the like and within a very short distance of said front gage. By this means, a more perfect preliminary straightening of the sheet is effected and the efficiency of the machine greatly increased. One of the 35 objects of the present invention is to provide improved means for causing the sheet-engaging members to travel near to the plane of feed during the movement of the carriages in one direction and to travel re- 40 moved from the plane of feed during the movement of said carriages in an opposite direction. Other and further objects will appear in the specification and be pointed out in the appended claims, reference being 45 had to the accompanying drawings in which,—

Figure 1 is a side elevation of paper-feeding mechanism provided with our improvements, parts being broken away; 50 Fig. 2 is a top plan view of the same; Fig. 3 is a fragmentary side elevation of the mechanism on an enlarged scale, parts being broken away and parts shown in section;

Fig. 4 is a fragmentary side elevation of 55 the track bar on an enlarged scale.

Fig. 5 is a fragmentary top plan view of 60 the track bar with a carriage mounted thereon;

Fig. 6 is a section on the line VI—VI, 65 Fig. 3, parts being shown in elevation.

Referring more particularly to the drawings, the main frame 1 of an automatic feeding machine, has mounted thereon suitable brackets 2, within which is journaled the 65 main cam shaft 3. A cam 4 on said cam shaft is adapted to engage a roller 5 carried by one end of a cam lever 6, which is journaled on a stud 7 carried by the bracket 2. A spring rod 8 having one end pivoted at 70 9 on the lower arm of lever 6 carries a spring 10 which is confined between a collar 11 and rod 8 and an apertured lug 12 within which the other end of the rod 8 reciprocates. The spring 10 serves to maintain the 75 roller 5 in running contact with the cam 4. The lower arm of the cam lever 6 is pivotally connected at 13 with one end of a connecting rod 14, the other end of said rod being pivotally connected at 15 to a lever 80 arm 16 which is keyed to a rock shaft 17. Also keyed to the rock shaft 16 is an operating arm 18 which is pivotally connected at 19 with one end of a connecting rod 20, said rod 20 being connected at its other end 85 to a stud 21 which projects laterally from a carriage 22. As shown in Fig. 2, the present embodiment of my invention provides a pair of the laterally spaced carriages 22 which are reciprocably mounted on suitable 90 track bars 23, said track bars being respectively secured to the bracket arms 24 which depend from their hubs which are adjustably mounted on a transverse rod 26. By an inspection of Fig. 2, it will be seen that the 95 connecting rod 14 transmits a rocking movement to the shaft 17 which is therefore adapted to simultaneously reciprocate the carriages or slides 22. Referring now more especially to Figs. 3 and 4, each of the track 100 bars 23 is provided with a longitudinal groove 27 in one face thereof. A cam block 28 is rigidly secured to the track bar 23 adjacent the forward end of the groove 27. Another cam block 29 is secured to the track 105 bar within the groove 27 adjacent the rear end of said groove. A laterally projecting pin 30 within the groove 27 serves to journal

one end of a cam bar 31, said cam bar being provided with a facet 32 which is adapted to rest against the inclined face of cam block 28 (see Fig. 4). Said cam bar is 5 moreover provided with a cam surface 33 over which runs a cam roller mounted on the sheet engaging member to be herein-after referred to.

As shown in Figs. 3, 5, and 6, the carriage 10 comprises a hollow frame member 34 which is provided above and below with lateral flanges 35 which serve to guide it on the track bar 23. A gib is interposed between the upper side of the frame 34 and the track 15 bar 23, being adjusted vertically by screws 37. A side frame 38 coöperates with the flanges 35 to prevent lateral displacement of the carriage. On a stud 39 which projects from the lateral face of a slide or gripper 20 per member 40 is journaled a cam roller 41. A pin 42 projecting from the other face of the slide 40 has pivoted thereon one end of a rod 43 upon which is mounted a spring 44 which is interposed between an apertured 25 end 45 of said rod and abutment 46 which projects from a yoke 47 constituting a guide for the slide 40. Said slide 40 is provided below with an elongated foot 48 (see Fig. 3) to which is secured a gage member 49, said 30 gage member being provided with oppositely disposed branches 50 with downwardly turned flanges 51 which are adapted to be interposed in the path of travel of a sheet which is being fed forward to a printing 35 press or like machine. A plate 52 which is secured to the carriage by screws 53 has suspended from its lower end, a shoe or plate 54 with an upturned end 55 presented rearwardly to deflect the forward edge of a sheet 56 which is being fed forwardly by the tapes 57 which pass around a suitable roller 58. A flexible plate or leaf-spring 59 is secured at its rear end to the upturned portion 55 of the plate 54. The forwardly 45 presented end of this spring is adapted to lie flat against the plate 54, said plate being provided with an aperture 60 through which the lower end of a screw 61 may pass to impinge the forward end of the spring 59 at 50 each downward movement of the slide 40. Screw 61 is threaded into plate 49 carried by said slide 40. As shown in Fig. 3, during the forward movement of the carriage, cam roller 41 moves downwardly over the 55 inclined face of cam block 29 and traverses the lower run of the groove 27 in the track bar. During this movement the slide 40 is in lowered position so that screw 61 depresses the forward end of spring 59 into 60 position to form a member which gradually confines the movement of a sheet 56 which is thus gradually retarded until its forward edge hits the downturned flanges 51 after which its travel cannot exceed in speed the 65 movement of the carriage. Inasmuch as the

laterally spaced carriages move in unison, it will be seen that if the forward edge of sheet 56 on one side of the machine is in advance of said edge on the other side of the machine it will be retarded on the advanced side in such a manner as to substantially straighten the forward edge of the sheet before it moves into engagement with the front 70 gages 62 of the printing press or the like.

As the carriage reaches the forward end of 75 this movement, cam roller 41 mounts the inclined face of cam block 28 thus forcing slide 40 upwardly and lifting gage flanges 51 away from the path of the sheet to release said sheet. At the same time spring 59 is permitted to lift while, the carriage assumes a position which permits the return 80 movement thereof with the roller 41, traveling first over the cam face 33 on the end of cam bar 31 and thence over the upper 85 run of said cam bar back to the initial position to control the forward movement of the next succeeding sheet.

We claim:

1. The combination with sheet conveying 90 tapes of a carriage reciprocating in the direction of feed of said tapes, means for reciprocating said carriage at a rate of speed slower than the movement of said tapes, means carried by said carriage and capable of being 95 raised and lowered to more or less confine the edge of a sheet, a sheet gage carried by said carriage, and means for raising and lowering said sheet gage.

2. The combination with sheet conveying 100 tapes, of a carriage reciprocating in the direction of feed of said tapes, means for reciprocating said carriage at a rate of speed slower than the movement of said tapes, means carried by said carriage and capable 105 of being raised and lowered to more or less confine the edge of a sheet, a sheet gage carried by said carriage, and means for raising and lowering said sheet gage, said raising and lowering means being adapted to move 110 said sheet confining means.

3. The combination with sheet-conveying 115 tapes, of a reciprocable carriage traveling at a slower rate of speed than said tapes, a gage mounted on said carriage to move into and out of position to intercept a sheet fed by said tapes, a yieldable member suitably supported by said carriage to confine the movement of a sheet fed by said tapes, and means interengaging between said gage and 120 said yieldable member to vary the position of the latter.

4. The combination with sheet-conveying 125 tapes, of a reciprocable carriage traveling at a slower rate of speed than said tapes, a gage mounted on said carriage, means for raising and lowering said gage, a guide foot depending from said carriage, a movable leaf carried thereby, and means operated by the gage for moving said leaf to more or less 130

confine the movement of a sheet as it approaches said gage.

5. The combination with sheet-conveying tapes, of a reciprocable carriage traveling at a slower rate of speed than said tapes, a gage mounted on said carriage, means for raising and lowering said gage, a guide foot depending from said carriage, a movable leaf carried thereby, and means operated by 10 the gage for moving said leaf to more or less confine the movement of a sheet as its approaches said gage, said leaf being secured adjacent its rear end to said foot and having its forwardly extending end tending to 15 lie snug against said foot, said gage being provided with an abutment for engaging said forward end of the leaf.

6. The combination with relatively fast moving sheet-conveying tapes, of a relatively slow moving reciprocable carriage, a yieldable sheet-confining member mounted on said carriage, a slide reciprocable on said carriage, a gage carried by said slide, means operated by said slide for moving said yieldable sheet-confining member, and means for reciprocating said slide.

7. The combination with relatively fast moving sheet-conveying tapes, of a relatively slow moving reciprocable carriage, a yieldable sheet-confining member mounted on said carriage, a slide reciprocable on said carriage, a gage carried by said slide, means operated by said slide for moving said yieldable sheet-confining member, and means for reciprocating said slide, said slide-reciprocating means including means for reciprocating said carriage.

8. The combination with relatively fast moving sheet-conveying tapes, of a relatively slow moving reciprocable carriage, a yieldable sheet-confining member mounted on said carriage, a slide reciprocable on said carriage, a gage carried by said slide, means operated by said slide for moving said yieldable sheet-confining member, and means for reciprocating said slide, said slide-reciprocating means including a cam having upper and lower runs, a cam roller journaled on said slide and successively traversing said runs, and means for moving said cam roller from one of said runs to the other at each end of the reciprocatory movement of said carriage.

9. In a machine of the character described, the combination of a track bar, a carriage 55 reciprocable on said track bar, a slide reciprocable on said carriage, said slide being provided with a cam roller and sheet-engaging means, and a cam having upper and lower runs over which said cam roller 60 runs successively.

10. In a machine of the character described, the combination with a track bar, of a carriage reciprocable thereon, said track bar being provided with a cam run with a 65 lowering cam at one end and an elevating cam at its other end, a cam bar pivoted above said cam run and having a cam run extending along its upper edge, sheet-engaging means reciprocably mounted on said 70 carriage, and a cam roller which imparts the reciprocating movements to said sheet-engaging means, said cam roller being suitably mounted to successively travel the said cam runs.

11. In a machine of the character described, the combination with a reciprocable carriage, sheet-engaging means movable up and down thereon, a cam roller connected with said sheet-engaging means, and a cam 80 bar provided with a run which permits said roller to drop during the forward movement of said carriage and raises said cam roller adjacent the end of such forward movement, and a second cam bar movable into and out 85 of position to lift said cam roller during the return movement of said carriage.

12. In a machine of the character described, the combination with a reciprocable carriage, sheet-engaging means movable up 90 and down thereon, a cam roller connected with said sheet-engaging means, and a cam bar provided with a run which permits said roller to drop during the forward movement of said carriage and raises said cam roller 95 adjacent the end of such forward movement, and a second cam bar movable into and out of position to lift said cam roller during the return movement of said carriage, the second mentioned cam bar being pivoted at one 100 end to the other cam bar and having its free end provided with a cam surface for elevating said cam roller at the beginning of the return movement of said carriage.

THOMAS E. BREEN.
